WALDEMAR KOPS, OF NEW YORK, N. Y., ASSIGNOR TO KOPS BROS., OF NEW YORK, N. Y.,
A FIRM.

ELASTIC FABRIC.

1,044,890.

Specification of Letters Patent.

Patented Nov. 19, 1912.

Application filed September 23, 1911. Serial No. 650,958.

To all whom it may concern:

Be it known that I, WALDEMAR KOPS, a citizen of the United States, residing at the borough of Manhattan, in the city, county, and State of New York, have invented an Improvement in Elastic Fabrics, of which the following is a specification.

My invention relates to elastic fabric of parallel sided form, with the object of providing fabric suitable for use between parts under tension, in gores of corsets, slippers, etc. and wherever such forms of elastic are useful in the arts and manufactures.

In the article of my invention I provide the elastic portions with borders or edges of inelastic fabric forming sewing sections, and in the continuous flat strip as woven the inelastic sewing sections are arranged intermediate the elastic sections transversely or in diagonal reversed positions adapting the strip to be cut up through the inelastic sewing sections into shaped pieces of suitable configuration for filling the gores of corsets, slippers etc. In each of these parts the elastic strands run parallel with the warp threads and in the sewing sections the elastic and usual warp threads are bound together both by the usual weft threads and by additional and intermediate weft threads, whereby the elastic warps are firmly held in place and slipping thereof prevented.

I prefer to form the elastic fabric of my invention in continuous lengths, which are adapted to be severed at intermediate points or cut up into suitable shaped sections.

In the drawing I have shown a plan of a length of elastic fabric according to my invention.

Similar letters and numerals of reference indicate similar parts.

In the drawing 2 and 3 represent the selvage of the elastic fabric strip, a , a^1 , a^2 , a^3 and a^4 represent the in-elastic or sewing sections, b , b^1 , b^2 , b^3 and b^4 represent the elastic sections.

In the fabric of my invention the warp threads, of cotton or other suitable material, extend lengthwise of the fabric. The elastic strands run parallel to the line of and between groups of warp threads and preferably extend from selvage to selvage.

In weaving the fabric of my invention, and as illustrated, the parts a , a^1 , a^2 , a^3 and a^4 , contain additional weft threads of cotton

or suitable material, woven with the same or independent and separate shuttles in the transverse or diagonal lengths of figures illustrated, so that at one point a and a^1 come together, and a^2 and a^3 come together, while at the other end a^1 and a^2 come together and a^3 and a^4 come together, and these series are thus reversed.

The fabric is adapted to be severed along the dotted or broken lines 4 centrally through the union of the respective inelastic or sewing sections a , a^1 , a^2 , a^3 and a^4 , and as thus severed the parts are adapted for filling in gores of the desired shape for the utilization of the elastic or yielding shaped parts thereof.

While I have shown the severable parts as of V-shape, they may be of U or other shape according to the use to which said parts are to be put, without departing from my invention.

I claim as my invention:

1. A flat length elastic fabric having continuous elastic warps suitably spaced through its width and comprising elastic parts with relatively narrow marginal inelastic or sewing sections extending at an inclination across the direction of elasticity.

2. An elastic fabric having continuous elastic warps suitably spaced throughout its width and adapted to be severed into suitably shaped sections, each having opposite relatively narrow marginal inelastic or sewing sections which in the fabric before being severed extend at an inclination across the direction of elasticity.

3. A flat length elastic fabric adapted to be severed into suitable shaped sections, with opposite marginal in-elastic sewing sections and in which said shaped sections are woven continuous and reversed in position.

4. A flat length elastic fabric adapted to be severed into V-shaped sections, with opposite marginal inelastic sewing sections and in which said sections are woven continuous and reversed in position.

5. A flat length elastic fabric adapted to be severed into suitable shaped sections, with opposite marginal in-elastic sewing sections and in which said shaped sections are woven continuous and also in which additional weft threads form, with the usual weft threads and the warp, the marginal inelastic or sewing sections.

6. A flat length elastic fabric adapted to be severed into suitable shaped sections, with opposite marginal in-elastic sewing sections and in which said shaped sections are woven continuous and also in which additional weft threads form, with the usual weft threads and the warp, the marginal in-elastic or sewing sections extending across the strip of webbing diagonally.
- 10 7. A flat length elastic fabric adapted to be severed into V-shaped sections, with opposite marginal in-elastic sewing sections

and in which said sections are woven continuous and reversed and also in which additional weft threads form, with the usual weft threads and the warp, the marginal in-elastic or sewing sections extending across the strip of webbing diagonally.

Signed by me this 14th day of September 1911.

WALDEMAR KOPS.
